UNITED STATES PATENT OFFICE

2,543,436

APPARATUS FOR PAINTING WALLS

Stephen P. Chappan, Carbondale, Pa., assignor to
 Universal Surface Machines, Inc., Philadelphia,
 Pa., a corporation of Pennsylvania

Application March 28, 1947, Serial No. 737,841

4 Claims. (Cl. 91—44)

1

My invention relates to a method and apparatus for applying paint and more particularly to a method and apparatus for painting ships, buildings and the like.

An object of my invention is to provide an improved method and apparatus for painting exterior and interior surfaces of ships, buildings and the like.

Another object of my invention is to provide an improved painting apparatus wherein the paint applicator is adapted to be automatically moved vertically and transversely of the surface to be painted.

Yet another object of my invention is to provide painting apparatus having improved means for automatically projecting the paint applicator support a predetermined distance vertically of the surface to be painted when the applicator reaches the limit of its travel transversely of said surface.

Still another object of my invention is to provide painting apparatus constructed and arranged whereby the exterior hull portions of a ship, including bow and stern, may be painted while the ship is afloat.

A further object of my invention is to provide an improved apparatus for painting ships, buildings, and the like, designed to eliminate the necessity of using scaffolds, stagings, ladders, or similar temporary painter's support devices.

A still further object of my invention is to provide improved apparatus for painting ships wherein the paint applicator assembly is slidably mounted upon its support, the applicator being adapted to move in a plane perpendicular to the support.

With these and other objects in view, which may be incident to my improvements, the invention consists in the parts and combinations to be hereinafter set forth and claimed, comprising my invention may be varied in construction, proportions and arrangements, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawings:

Figure 1 is an elevational view of the trackway and carriage arrangement used to support

2

the paint applicator in desired position for applying paint to a ship.

Fig. 2 is an elevational view of a modified form of device adapted for painting buildings, silos and the like.

Fig. 3 is a perspective view of a bracket or clamp used to support the trackway on the rail of a ship.

Fig. 4 is a detail view of the arrangement for raising the paint applicator support.

Fig. 5 is a detail view of the trip mechanism and feed device used to advance the applicator support sections to operative supporting position.

Fig. 6 is a detail view of one end of an applicator support section.

Fig. 7 is a perspective view of the paint applicator assembly.

Fig. 8 is a detail view showing a trip device and associated mechanism for projecting the applicator support when the carriage reaches the limit of its travel, lengthwise of the trackway.

Fig. 9 is an elevational view of the telescopic support arrangement used with the modification shown in Fig. 2.

Fig. 10 is a detail view of the arrangement used to elevate the trackway of the modified device shown in Fig. 2.

Fig. 11 is a detail view showing the joint between two of the telescopic members shown in Fig. 9.

Fig. 12 is a detail view of the bottom support unit shown in Fig. 10; and

Fig. 13 is a detail view of the bearing arrangement for the top and bottom telescopic support units shown in Fig. 10.

The painting device of the present invention consists essentially of a trackway adapted to be horizontally supported in spaced relationship with respect to the surface to be painted, a carriage movable lengthwise of the trackway, an extensible support arrangement for a paint applicator mounted upon the carriage, means to move the carriage transversely of the trackway, and means to automatically project the applicator assembly support a predetermined distance vertically of the surface to be painted, when the carriage reaches the end of its travel lengthwise of its trackway. In the preferred form of the apparatus, the trackway is adapted to be supported from the rail of a ship and the extensible support means for the applicator assembly comprises a plurality of unit sections adapted to be moved to operative supporting position, and extended a predetermined distance

vertically of the hull of the ship, when the carriage reaches the end of its travel fore and aft. The applicator assembly is slidably mounted at the end of the extensible support means, and is adapted to move in a plane perpendicular to the plane of the extensible support.

When the carriage is moved lengthwise of the trackway, paint is applied to the hull of the ship in the form of a comparatively narrow band or strip, and after the carriage reaches the limit of its travel, fore or aft, the applicator assembly support is projected a predetermined distance less than the width of the applied band of paint, whereby paint is applied in successive overlapping strips as the carriage moves along the trackway. When it is desired to paint the hull and stern surfaces, the applicator is maintained a constant distance from the curved surfaces thereof through the medium of the slideable connection between the applicator and its support at the end of the extensible member.

In the modified form of apparatus, for use in connection with the painting of silos, buildings and the like, the trackway together with the movable carriage and associated paint applicator is mounted upon a telescopic type support whereby the trackway may be moved vertically of the wall of a building or other surface to be painted.

The device of the present invention may be used to paint a ship's hull when underway at sea, at anchor, moored to a dock, dry-docked or in a shipyard. Weather conditions permitting, the ship's hull and a considerable portion of the deck structure may be painted while loading or discharging cargo. The device may be used ashore for painting walls and ceilings of oil storage tanks, barns, silos, houses and other buildings.

Referring to the drawings and more particularly to Fig. 1, the paint applicator support arrangement comprises a pair of I-beams 1, having tracks 2, attached to the top flanged portions 3 of the beams. A carriage designated generally by numeral 4, adapted to be moved lengthwise of the trackway, comprises a rectangular member 5 having legs 6 provided with wheels or rollers 7 adapted to seat in the tracks 2. Movement of the carriage lengthwise of the trackway is effected by means of a drive arrangement comprising a belt 8, connected at one point to the carriage, pulleys 9 and 9' and motor 10. The motor is mounted upon a bracket or other suitable support 11 attached to the end of one of the beams, shaft 12 of the motor being connected through suitable gears 13 and 14 to the spindle 15 of pulley 9. Means, not shown, are provided for automatically reversing the motor or the driving gears associated therewith, when the carriage reaches the limit of its travel in the vicinity of the opposite ends of the trackway.

In order to accommodate the applicator support arrangement to desired units of length of the surface to be painted, the trackway and supporting beams are constructed and arranged for longitudinal adjustment. The end portion 16 of the support, for example, is designed for telescopic engagement with portion 17. Suitable plates 18, formed with apertures 19, adapted to register with apertures 20, in the web portion of the I-beam, together with fastening devices 21, are used to securely hold the parts in adjusted position. Belt adjustment is effected by means of the slideable support 22 of pulley 9. The applicator support, as above described, is adapted

to be positioned in the vicinity of deck level of a ship, for example, on the ship's rail or other suitable support, by means of clamp devices 23 attached at spaced points on the underside of the bottom flange portion of the inner I-beam. Brackets of the type shown in Fig. 3, comprising a base 24 adapted for attachment to the bottom flange of the outer I-beam, swivel joint 25, extensible arm 26 and clamp member 27, designed for engagement with the hull of a ship, provide additional support for the trackway, in overhanging relationship with a hull portion of a ship.

Attached to the carriage and movable therewith is a housing designated generally by numeral 28, adapted to contain a plurality of unitary applicator support members 29. The housing comprises vertical side pieces 30 and 31, having top and bottom channelled members 32 and 33 respectively, secured thereto. The housing is rigidly attached to the carriage 4 by means of brackets 34 and 35, brace 36 and braces 37. In order to prevent accidental tipping of the carriage, due to the weight of the housing or magazine 38, wheels or rollers 39, attached to brackets 38, are provided. The rollers 39, as shown, are adapted to ride on the overhanging top flange portion of the inner beam. In the vicinity of the lower end of vertical member 31 of the housing, channel member 33 is cut away to form an opening which registers with a chute member 40, through which support units 29 are projected, as will be described hereinafter.

Referring to Fig. 7, the paint applicator assembly comprises a spray gun designated generally by numeral 41, pivotally mounted as at 42, to member 43, attached to a bar 44 adapted for sliding movement in a housing or casing 45, having a vertical hollow member 46, rigidly supported thereon by means of collars 47, and braces 48 and 49. The upper end portion of member 46 is reduced as at 50, and opposite faces of the member are provided with spring hooks 51 or other suitable fastening devices, the purpose of which will be described hereinafter.

Rotatably mounted within member 46 is a cylindrically shaped rod 52 having a gear 53 keyed to its lower end, adapted for engagement with a rack 54 positioned adjacent the casing. One face of the base portion of member 46 is apertured as at 55, to receive suitable drive means, not shown, whereby rod 52 may be rotated. It will thus be seen that when gear 53 is rotated, housing 45 and bar 44 to which the spray gun 41 is attached, moves lengthwise of rack 54.

Under certain conditions of operation, it may be found necessary to extend the gun a substantial distance outwardly from the housing and, accordingly, additional sections 44' may be added. In order to counter-balance the weight of the spray gun, when in extended position, a suitable counter-weight 56 is provided. The weight, as shown, is supported by rollers 57 adapted to seat in a flanged member 58 positioned below the housing 45. A suitable cord 59 or other flexible member, threaded over pulleys 60, has its free ends attached to opposite faces of the weight. By means of this arrangement the weight is moved to counter-balancing position when the spray gun is extended outwardly of the housing.

Referring to Figs. 1 and 7, the applicator assembly is supported in operative painting position by inserting housing 45 in the chute member 40, associated with the carriage 4, the reduced

end 50 of member 46 being adapted to seat in the lower end of one of the unitary support members 29 contained within the magazine 28. When member 46 is thus positioned, the spring hooks 51 seat in apertures 54 formed longitudinally of the opposite faces of the unit 29. The magazine 28 is designed to contain ten unitary support members, each unit being approximately 4 feet long. When the carriage is caused to move lengthwise of the trackway, the support sections are advanced a predetermined distance of the housing in the direction of the opening to chute, by means of a feed screw 62 adapted to be actuated by a trip member 63 mounted on the trackway. When feed screw 62 is rotated a pusher bar arrangement 64, attached to member 65 which is in threaded engagement with the feeder screw, contacts the outside face of the end most support section, and thus advancing all of the sections within the magazine 28, in the direction of operative supporting position.

Referring to Fig. 5, it will be noted that the end of the feeder screw 62 is provided with an extension 66 having a ratchet wheel 65 and star wheel 66 attached thereto. Rotation of the feeder screw is effected by means of the star wheel which is adapted to contact members 67 of the trip device, as the carriage moves over the trip during its passage lengthwise of the trackway. Reverse movement of the feed is prevented by means of a dog 68 arranged to contact the teeth portions of the ratchet wheel.

In order to project a support section 29 from the housing trip means are provided at opposite ends of the trackway. Referring to Fig. 8, a trip device designated generally by numeral 69, is adapted to contact a star wheel 70 attached to a rotatable shaft 71 supported in a bearing member 72, the shaft having a toothed wheel 73 keyed thereto. The toothed wheel is positioned so that a portion of its periphery extends into a slot or other aperture formed in one of the faces of the chute member, the teeth 74 of the wheel being adapted for engagement with apertures 75 formed in one of the faces of the housing of a support section. It will thus be seen that when the star wheel 70 contacts the trip device, wheel 73 is rotated and the support section is advanced from the housing.

Means are provided to check the downward drop of the support section, after it has been advanced, as above described, comprising a dog 76 pivotally mounted upon a bracket 77 attached to the chute member. Mounted upon an arm 78 is a pivotally supported wheel 79, arranged to contact extension 80 associated with the trackway. The end portion 81 of the pivotally mounted member 76 is adapted to seat in one of a plurality of recesses 82 formed longitudinally of the front face of the housing of the support section. As the carriage reaches the end of the trackway, roller 79 contacts member 80 causing the end 81 of member 76 to be withdrawn from the aperture in the housing, thus freeing the support section for downward movement when wheel 73 is rotated by the trip device 69.

In the operation of the device, so far described, when the motor 10 is operated, carriage 4 through the medium of belt 8 is moved back and forth over the trackway. When the carriage moves from left to right it passes over the trip device at the left end of the trackway without actuating the feed mechanism for the applicator support, however, when the carriage returns to the left it contacts the trip device at the right end of the track-

way causing the vertical extension which is connected to the applicator support, to extend a distance of four inches from the magazine, thus enabling the spray gun to reach a new surface. After the carriage reaches the limit of its travel to the left of the trackway and starts back, contact is made with the trip at the left end of the trackway and the extension is again extended a distance of four inches.

After the carriage 4 has moved from right to left of the track six times and from left to right six times, the four foot section has been dropped a total of four feet in twelve four-inch intervals. If the length required for the applicator support is greater than four feet, another section 29 is added so that a more distant surface can be reached by the applicator. When the twelfth four-inch drive has been substantially completed, the next extension has been moved within the magazine 28 into registering position with the chute so that it automatically becomes rigidly and securely fastened to the top length of the section which has been projected from the magazine. The second vertical extension is thus brought into position ready for locking by the feed screw 62 and associated feeder bar 64, which moves a constant distance each time the first extension drops four inches.

Referring to Fig. 6, it will be noted that the end of the shaft 52 within the tubing 46 is formed with a hexagonal shaped end 83. The purpose of this arrangement is to assure proper contact between adjacent rods when the individual support sections are moved into operative supporting position. By means of a key 84 the rods 52 are connected whereby rotation of any one of the rods by applying a wrench or other tool to shoulder position 85 causes rotation of gear 53, thus moving the spray gun support outwardly from the housing 45, to conform with the contour of the surface of a ship, for example, the hull portion.

Referring to Fig. 4, there is shown a detailed view of the arrangement used to raise the applicator assembly after the painting operation has been completed, that is to say, after the sections have been projected from the magazine and the applicator assembly is in its lowermost position. The face 86 of each of the unitary support sections (Fig. 1), is provided with a plurality of longitudinally spaced apertures 87 adapted to receive the teeth 88 of a star wheel 89. The star wheel is mounted upon a suitable shaft 90 adapted to be rotated through the medium of gears 91, 92 and 93, the latter gear being mounted upon a shaft 94 associated with a source of power, not shown. When it is desired to raise the applicator support sections, power is applied to shaft 94 and through the medium of star wheel 89, which engages with the apertures 87, the extensions are moved upwardly to a position at which they may be manually disconnected one from the other and stored in the magazine 28.

In the modification (Fig. 2), adapted for use ashore, in connection with the application of paint to silos, buildings and the like, the construction and arrangement of the trackway is substantially the same as shown in Fig. 1, however, in lieu of the magazine and associated support sections, for extending the applicator vertically of the surface to be painted, the trackway support is designed for vertical movement.

Referring to Fig. 2, the trackway is mounted on wheeled supports 95 and 96, adapted to be maintained in desired spaced relation by means

of collapsible carriage devices, designated generally by numeral 97. The carriage 98 is supported upon suitable rollers 99 adapted to ride on the lower flange portions of the I-beams.

Mounted within the carriage is a socket member 100, adapted to receive the end 50 (Fig. 7) of the vertical support 46 of the applicator assembly. In connection with the positioning of the applicator, as above described, it will be understood that the applicator is inverted from the position shown in Fig. 7, and when thus assembled the spray gun can be reversed so as to be supported above member 43, by means of connection 42.

Attached to the bottom 101 of the carriage 98 by means of a bracket 102, is a rotatable shaft 103 having a gear 104 keyed thereto, the upper end of the shaft terminating in a hexagonal shaped portion similar to the end arrangement shown in Fig. 6. The gear 104 is adapted to mesh with gear 105 attached to a shaft 106, rotatably supported in a bracket 107, the end of said shaft having one part of a chuck device 108, attached thereto. It will thus be seen that when shaft 103 is rotated, gear 53 on the applicator support assembly (Fig. 7) is rotated thereby by moving the spray gun outwardly of its support.

Referring to Fig. 10, the trackway support 95 is shown in partially elevated position. It will be noted that each of the supports, 95 and 96, comprises a plurality of telescopic rectangular shaped members 109 and cylindrical shaped members 110, positioned therein. The bottom rectangular shaped member is attached to a base 111, mounted upon wheels 112. The opposite edges of each of the rectangular shaped sections at the top and bottom thereof, are provided with rollers 113 (Fig. 11) whereby, when the sections are moved with respect to one another with minimum friction. The cylindrical telescopic sections 110 (Fig. 9) are formed with a slot 114 and pin 115 arrangement to limit the upward movement of each of the sections. Vertical movement of supports 95 and 96 is effected by means of cables 116 and 117 (Fig. 2) threadable over suitable pulleys 118 and 119. One end of each of the cables is attached to a drum 120, the cables being adapted to be wound thereon, by means of a motor 121. The free ends of the cables are attached to the top rectangular member of the respective supports 95 and 96, whereby when the drum is rotated the sections are moved upwardly to desired height, that is to say, the height at which the applicator assembly is in operative painting position.

Again referring to Fig. 10, means are provided for rotating the inner cylindrical sections comprising a stub shaft 121 having a notched end 122 adapted to seat in a recess formed in the lowermost cylindrical section. The shaft is supported in a bracket 123 and is provided with a gear 124 adapted to mesh with gear 125, mounted upon a shaft 126 which terminates in a handle member 127. The top cylindrical section is also provided with a stub shaft 128, gear 129 adapted to mesh with gear 129 mounted upon a shaft 131. The shaft 131 is journaled in brackets 132 and 132', the free end of said shaft having a chuck portion 133 adapted to seat in member 108 (Fig. 2) at the end of the shaft 106, carried by the carriage 98.

In the operation of the modified form of apparatus, so far described, assuming the paint applicator assembly has been mounted in operative position on the carriage 98, the supports 95 and

96 are elevated to required height by means of motor 121. After the supports have been rolled to proper position with respect to the surface to be painted, the carriage, together with the applicator assembly is caused to move lengthwise of the trackway by means of belt 8, which is actuated by motor 10. It will be understood that paint is supplied to the spray gun 41, from a suitable source, not shown, simultaneously with the movement of the carriage. When the carriage reaches the limit of its travel to the left of the trackway, stop member 134 attached to bracket 135 of the carriage contacts a switch device 136, connected by leads 137 to the motor 121, whereby the motor is reversed, to permit the cables to unwind, and lower the supports 95 and 96, substantially four inches. When the carriage reaches the limit of its travel to the right of the trackway, stop member 138 contacts a switch device, not shown, similar to switch 136, whereby the supports are again lowered a distance of approximately four inches.

If during initial positioning of the apparatus, or at some stage of the painting operation, it is desired to move the spray gun outwardly of its support in the direction of the surface to be painted, the carriage is moved to the left of the trackway to a position such that member 103 fits over member 133 and in driving engagement therewith. Handle 127 is then rotated, and through the medium of stub shaft 121, cylindrical telescopic sections 110, shafts 128, 103 and associated gears, the applicator support is caused to move outwardly of its support.

As shown in Fig. 12, the lowermost cylindrical section 110 is rotatably supported on members 139 attached to the rectangular shaped bottom section 109 and to a stationary ring 140. A plurality of roller bearings 142 are provided between the bearing surfaces of the ring and flange portion formed on the lowermost cylindrical section. Similar means are provided to connect the uppermost cylindrical section 110 to the uppermost rectangular shaped section 109.

The device of the present invention is compact, and it can be readily assembled or disassembled; it can be conveniently stored or shipped and when started it operates automatically to apply paint to desired surfaces, with minimum expense.

It is to be understood that the basic concept of supporting a paint applicator, as described herein, comprehends the use of other devices in lieu of a spray gun, for example, a paint chipping device, a rotatable brush for removing foreign material preparatory to painting a surface, a polishing head or the like.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention or exceeding the scope of the appended claims.

I claim:

1. A device of the character described for painting walls of buildings comprising an elongate, horizontally supported trackway adapted to be positioned in spaced, generally parallel relationship with respect to a wall of the building, a plurality of telescopic members for supporting said trackway, a wheeled carriage movably mounted on said trackway, a stop member and a paint spray means supported on said carriage,

power means to move the carriage back and forth along the trackway, means to automatically reverse said power means when the carriage reaches the end of its travel, a motor, an elevating mechanism drivingly connected to said motor, means connecting said elevating mechanism to said telescopic members, and control means for automatically operating said motor, said control means including a switch mounted on said trackway and in the path of said stop member, said switch being closed by said stop member on said carriage and maintained in closed position only while the carriage is at the end of its travel, whereby said trackway is moved a predetermined small distance vertically while said switch is closed, and means including telescopic means for actuating said extensible support means.

2. A device of the character described for painting walls of buildings comprising an elongate, horizontally supported trackway adapted to be positioned in spaced, generally parallel relationship with respect to a wall of the building, a plurality of telescopic members for supporting said trackway, a wheeled carriage movably mounted on said trackway, a stop member and a paint application assembly supported on said carriage, said assembly comprising a spray means and an extensible support means for said spray means, power means to move the carriage back and forth along the trackway, means to automatically reverse said power means when the carriage reaches the end of its travel, a motor, an elevating mechanism drivingly connected to said motor, means connecting said elevating mechanism to said telescopic members, control means for automatically operating said motor,

5
10
15

said control means including a switch mounted on said trackway and in the path of said stop member, said switch being closed by said stop member on said carriage and maintained in closed position only while the carriage is at the end of its travel, whereby said trackway is moved a predetermined small distance vertically while said switch is closed, and means including telescopic means for actuating said extensible support means.

3. The structure set forth in claim 1 wherein said elevating mechanism comprises a drum, and said connecting means comprises pulleys on said telescopic members and a cable trained over said pulleys and around said drum.

4. The structure set forth in claim 2 wherein said elevating mechanism comprises a drum, and said connecting means comprises pulleys on said telescopic members and a cable trained over said pulleys and around said drum.

STEPHEN P. CHAPPEN.
